(57) CLAIM

The ornamental design for a pressure sensor, as shown and described.

DESCRIPTION

FIG. 1 is a rear perspective view from above and to the right of the pressure sensor according to the invention, the perspective view from the left is a mirror image thereof.

FIG. 2 is a front perspective view from below and to the left of the pressure sensor according to the invention, the view from the right is a mirror image thereof.

FIG. 3 is a front elevation of the pressure sensor according to the invention; and,

FIG. 4 is a left side view of the pressure sensor according to the invention, the right view is a mirror image thereof.
